TO SICILIAN ASPHALT PAVING CO., OF NEW YORK, N. Y., A CORPORATION OF NEW YORK.

ROAD CONSTRUCTION.

No. 909,499.

Specification of Letters Patent. Patented Jan. 12, 1909.

Application filed May 2, 1908. Serial No. 430,483.

To all whom it may concern:

Be it known that we, FREDERICK F. WILLIAMSON and DANIEL BRENNAN, Jr., both citizens of the United States, and residents of the borough of Manhattan, city, county, and State of New York, have jointly invented certain new and useful Improvements in Road Construction, of which the following is a specification.

10 Our invention relates to the construction of streets or roads, and has for its object to obtain a strong and efficient supporting body with a smooth, durable, semi-elastic, dustless and non-slippery wearing surface. For this purpose we have devised a novel construction involving the use of stone and asphalt arranged and compacted in an improved manner, as we shall now proceed to describe.

Reference is to be had to the accompanying drawings in which—

Figure 1 is partly a cross-section and partly a perspective view (with parts removed), illustrating the construction of our improved road; Fig. 2 is a partial elevation of a roller employed by us in making such road; and Fig. 3 is a top view of another form of roller.

On a proper road bed A we spread, loosely, enough clean broken stone B of a substantial and uniform size to make a finished layer able to support the weight of the traffic. For this we prefer hard and tough stone, such as trap rock, of a size which would pass through a two and a quarter inch ($2\frac{1}{4}$) ring and free from all pieces small enough to go through an inch and an eighth ($1\frac{1}{8}$) ring. For softer and more friable stones we prefer a size larger, say $2\frac{1}{2}$ " rejecting $1\frac{1}{4}$ " to 3", rejecting $1\frac{1}{2}$ ". On a good road bed a layer of loose stone 6 inches thick, rolled down to about 4 inches thick is usually sufficient. The loose bed of stones will have about 45% of voids and the finished layer about 12% of voids. We roll this loose, unpacked layer of clean stones with a heavy roller (an ordinary self-propelled roller of about 15 tons weight will do, or by means of a grooved roller such as referred to herein-after), adding as the rolling progresses, fresh, clean stones of the same quality and size to work into and thicken the layer if necessary, and in like manner, and by further rolling, we fill all depressions and remove surplus stones from high places until the

surface of the layer is brought to the required grade and refuses to go any lower. (It is well understood that in this layer B we do not use any fine stuff that would act as a binder.) The stones being clear of binding material or filler of any kind, do not remain in their accidental relative positions as spread, but are forced by the action of the roller to find their best bearings upon the road bed and upon, and between each other. The smaller stones and pieces broken off by the pressure and movement of the roller find their way to the bottom, while the good sized strong stones are forced to collect at the top of the layer (where they remain) pressed and crowded together, face up, in horizontal alinement; and though the stones in the layer are not as yet in any sense bound together, they lie closer and have a stronger and more effective bearing upon and between one another, than if a binder of any kind, or a mixture with finely crushed stones, grit, gravel, sand or earths were used, or if a mixture of asphalt or any fine stuff were present. The rolling operation therefore securely anchors or bonds the stones of the lower layer. Care being taken to keep this compact layer B of clean stones and its alined surface intact as finished by the roller, we flood it with enough soft asphalt, heated to a liquid consistency, to fill all the voids and interstices in the layer and at the same time to overflow the surface thereof to such a depth (usually about $\frac{1}{2}$ "), as may be necessary to bond and cushion the wearing surface of the road, as hereinafter described.

The asphalt bituminous binder is poured on the surface and into the chinks in excessive quantity; the surplus is pushed forward as absorption into the layer ceases, leaving the required quantity behind on top of the layer. No mixture of fine stones or grit having been used, the hot asphalt runs in freely and fills to overflowing the voids in the layer B, but the stones comprising the layer being all of good size, especially at the surface, the asphalt does not in the least disturb the solid bearings they have upon and between one another, as brought about by the movement and pressure of the roller.

The asphalt we use is preferably of the best quality, as tough and soft as it can be made, without liquefying injuriously in hot weather. It can be made from various bi-

tuminous ingredients to suit our requirements by those skilled in the art. Generally speaking, an asphalt that will begin to melt at about 100° Fahrenheit, and will completely liquefy at about 300° Fahrenheit, is stiff enough for our purpose.

The melting and liquefying points of the soft asphalt are greatly modified (as far as the heat of the weather is concerned) by the presence of the stones therein. The asphalt is a very slow conductor of heat or cold and the stones embedded in it will take a long time to heat in response to weather conditions and as the asphalt itself will 15 cling fast and not liquefy until the stones buried in it are at the same temperature that will liquefy the asphalt, the heat of the day is passed long before this temperature is reached and the mass has time to cool off 20 again and resume the normal or average temperature which is not injurious to the road. We now apply the stone for the wearing coat C of the road, consisting, usually, of a mixture of small stones and 25 grit, as made by the crusher and screened out of the stones used for the under layer (generally called "coarse screenings"). (If this material comes in two grades, generally known as " $\frac{1}{2}$ " stone and "fine 30 screenings", the screenings or grit may be spread on first and the " $\frac{1}{2}$ " stone spread on top of it). This material we spread evenly over the bed of soft asphalt left for it upon the surface of the under layer, taking care 35 that it is well mixed and not all fine in one place and all coarse in another. The spreading is best done by hand on the spot from a heap on a so-called mixing board by expert spreaders who, with shovels, can mix 40 and apply it with a surprising regularity of mixture and quantity.

For hard and tough coarse screenings of trap rock there would be spread upon a half-inch bed of asphalt enough to make a 45 finished surface layer $1\frac{1}{2}$ inch thick including the asphalt. This will take unpacked screenings about $1\frac{1}{2}$ inch thick. A thicker bed of asphalt will take more screenings in proportion. If the screenings are from rock 50 of a friable nature they should be coarser in the first instance, as they will wear and cut down to a smaller size by the process of assortment and packing into place, used in finishing the road, as hereinafter described. 55 The coat of screenings will sink into and cover the bed of soft asphalt, making a rough surface which is then rolled and finished by a special roller as hereinafter described. We now use a special roller (Fig. 60 2 or Fig. 3 designed by us for the above purpose, and described hereinafter) to knead the screenings into the asphalt and at the same time to classify the screenings by forcing the good sized strong pieces of stone 65 therein to collect at the surface and the

smaller pieces and grit assemble in lower positions in the asphalt reaching to the under layer and into the chinks thereof. The top coat is thus graded in density, being nearly all stone at the surface (of the road) 70 and nearly all asphalt in the chinks of the under layer, there being a lesser proportion of stone or grit and more asphalt as the distance from the surface increases.

We use a stiffer asphalt and a larger proportion of fine grit or dust in the surface layer on steep hills facing the sun than we do on level ground and in shady places. We would use a stiffer asphalt in the Southern States than in New England, Canada, 80 or the Northwest, for example.

In the construction illustrated by Fig. 2, the roller D we use for this purpose has a number of ribs or annular ridges D' thereon and when it is properly proportioned as to weight and as to number, shape and dimensions of the ridges and of the spaces between and is used by running it backward and forward and in every direction upon the screenings and asphalt, it will rapidly knead the 90 stones into the asphalt and at the same time grade them and thereby vary the proportion of asphalt and screenings within the top layer as above described. To be durable and to be easily cleaned the roller should 95 have inclined faces on the side of its ribs or ridges. The width of the cylindrical surface of a rib should be about one-third of the interval between said surface, or in other words the aggregate width of these surfaces 100 should be about one-fourth of the roller's length. In order that the under layer may not be disturbed the depth of the grooves between said ribs should not be over about one-half of the thickness of the finished 105 layer C.

Both in rolling the stone of the layer B and of the upper layer, we secure an improved result by reason of the fact that the rolling operation brings about what may be called a classification of the material, that is, the larger stones are brought into the surface, while smaller ones seek lower levels. This beneficial action for our purpose may be explained as follows: If there is not too much binder present, and if the stones are clean as in layer B, the roller at first pushes a wave of loose stones ahead of it involving a movement among the stones which has a screening effect, allowing the small stones 115 to go to the bottom of the mass by gravity, whereby also the coarser stones are to that extent raised; then as the pressure of the roller comes on the edge of a stone, that stone is tilted up to an extent in proportion 120 to its size and smaller pieces get under the tilted end. By a repetition of this action the stones are soon graded the larger ones 125 being forced to collect at the surface of the layer. As the operation comes to a finish 130

the stones have found their best fitting places in the layer, the tilting-up action subsides and stops and the surfaces are face-up in horizontal alinement. It will thus be seen that classification can be easily brought about by an ordinary road roller of good weight under the conditions obtaining in our first comparatively coarse layer of stones; but to classify the screenings in the surface 10 layer C and in the presence of the asphalt requires a different and a more effective machine, so we provide therefor a number of narrow rollers, or disks, as it were, spaced apart, the rolling face of each disk having of 15 course two edges. A disk roller, as we may call it, as designed for our purpose, of the same weight and general dimensions as a plain roller, would be composed for instance of 16 disks having 32 angular edges, the aggregate rolling faces of the disk having 4 20 times the pressure on the road of a plain roller of the same size and weight.

A tilting effect of the edges of a ridge or ring on the stones in the layer is manifestly 25 much greater than can be produced by the rolling faces thereof, as after the stone is tilted up the roller passes by and gives time for small stuff to get under the tilted up end and very often forces smaller pieces under 30 such raised end by reaction. This kind of a roller will not push so much of a wave in front of it as a flat roller does, but induces a complexity of movements in the mass whereby the stones soon become classified and find 35 their best fitting places in the layer, the larger ones on top, thus with this form of roller the resistance of the soft asphalt to the classification of the stones into position is overcome and it progresses rapidly to completion.

The edges or ridges of the roller cut into the mass at first to the full depth thereof, but at each succeeding time of going over they cut in less and less, and finally do not 45 cut in at all, leaving the surface smooth with the best stones face up as described. The inclined faces D² adjacent to each of said edges or ridges, assist in crowding the stones sidewise so as to facilitate their rearrangement and classification. The rolling taking 50 place on a comparatively thin layer superposed on a firmly established alined surface of large stones, assists in the operation as also does a peculiar pumping action of the asphalt itself which begins almost immediately and is retained during the life of the rod.

The machine of which the grooved roller forms the working part may be a self-propelled one of usual character. Its steering-roll may be plain and not grooved, so that it 60 will flatten out the grooves made at first by the main roller. We prefer to provide means whereby the surface of the roller may be kept clean. We have illustrated such means

in conjunction with a somewhat different form of our roller shown in Fig. 3, which is characterized by the employment of spiral ribs D³ in lieu of the annular ribs of Fig. 2. The cleaning device in this case consists of a chain E suitably carried by the frame of the roller, the links of said chain being so formed as to conform to the outline of the ribs D³. Of course as the roller rotates the chain will be moved slowly and the grooves 75 between the spiral ribs as well as the faces of said ribs will be kept clean. With a roller having annular ribs as in Fig. 2 a simple toothed bar secured to the frame in such a way that its teeth would project between the ribs of the roller would be sufficient. The spirally ribbed roller of Fig. 3 has the advantage of a tendency to crowd the covering of the road toward the center, which is of assistance in giving the road the proper 80 transverse form with the center of the road higher than the sides. Of course it is understood that to accomplish this result the roller would be made to travel on one side of the road going in one direction and on the other 90 side coming back.

The surface of the road when rolled as described is composed of a coherent layer of stones with alined surfaces each stone being surrounded and held conjointly with its neighbors by a thin skin of asphalt. This crust-like surface has beneath it the smaller stones and grit, having proportionately more and more asphalt in it as the surface of the under layer is reached, the gritty 100 mixture extending more or less into the crevices of the under layer; the asphalt on the lower interstices of the under layer has little or no grit therein.

The connection and extension of the identical asphalt through and into both layers prevent the surface layer from being stripped off by the suction of heavy and fast automobile traffic. The surface layer is always elastic, has little or no supporting 105 resistance to the traffic, depending for this entirely on the under layer. We desire to call particular attention to the fact that the stones in the lower layer B are in supporting engagement with each other, so that the 110 weight of the traffic is borne by these stones and does not rest at all, or at least not materially upon the asphalt contained in said layer.

The coherent surface forms and acts as a 120 sort of diaphragm and sets up a compression and pumping action from the vibration of the traffic that exerts as a capillary suction clear down as far as the asphalt goes.

The wear of the surface is remarkably 125 small, as the stones comprising it are cushioned by the asphalt, not being directly between the wheels and the hard supporting surface as in the ordinary macadam road. The wear and the usual street dirt are just 130

about sufficient to keep the surface from becoming sticky from the slight amount of asphalt that squeezes up between the surface stones.

- 5 If any part of the road surface becomes defective for want of sufficient screenings or asphalt, such defects may be repaired by simply applying the required material and working it in with the special grooved roller.
- 10 By our system we can use the size of stone usually made by crushers and we can proportion the thickness and size of the stone in the two layers and the amount of asphalt needed in such a way as to use the whole product of a crusher from the maximum suitable size down.

By our system old macadamized roads can be resurfaced using the broken stone and screenings already in the road, the necessary asphalt only being added. Gravel will do for our surface layer and is often cheaper and better for the surface than screenings made from the country rock. When the asphalt cools, the stones in the under layer B are held in their strongest and most effective position to support the weight of the traffic and this strength will be more uniform throughout the layer because of the comparative uniformity of the size of the stone in the layer, it being nearly impossible to get an even consistency with a mixture containing fine stuff in such a layer. We can, however, get very good results in the layer B from any strong good sized broken stone that is clean and free from a detrimental proportion of chips and fines such as would prevent classification by the roller though care must be taken about this as any bound spots in the under layer would cause the stripping off of the upper layer by heavy automobile traffic. Small bonded or unclassified spots in the layer, however, can be to a certain extent, repaired, as it were, by hand with a heavy rammer before pouring the asphalt.

45 We do not want to be confined too closely, as there are many schemes of repair if the under layer is not well classified. It can be harrowed and then rolled, for instance so the top of the layer would be clean anyway, which though not as good as a layer clean all through, would be admissible sometimes when the question of cost is a controlling one.

Our system does not require expensive apparatus for assorting the stones and for heating and mixing them with the asphalt before laying. We force the best assortment of the stones for our purpose, as they lie in the road, by our rolling system and we get the best use of the asphalt constituent of the road by a single operation, also in place.

It will be seen that our road consists, substantially, of two layers of stone, an under layer of coarse stones and an upper layer of smaller stones forming with soft asphalt the wearing surface of the road; that both layers

are bonded by the same identical soft asphalt applied in a single operation without previous mixing with the stones of either layer, but that by previous rolling a stiff and firm under layer is produced while an elastic surface layer is obtained by putting the asphalt in place first, then applying the stones and rolling them into it to form a surface more or less elastic according to the proportion of stones in the layer. The non elastic base preserves the grade and crown of the surface layer, which is anchored fast to the under layer by the identical asphalt extending through both layers.

We claim as our invention:

1. In a road or the like, an under layer of comparatively large stones in supporting contact and set close together at the top of the layer parallel with the contour of the finished road, and an upper layer of smaller stones, the spaces between the stones of both layers and between the layers being filled with a soft bituminous binder of identical quality extending within both layers, the stones in each layer being classified so that the larger stones are near the top.

2. In a road or the like an under layer of coarse stones and an upper layer of smaller stones, the spaces between the stones of both layers and between the layers being filled with a soft bituminous binder of identical quality, the larger stones in each layer being at the top, face up, close together and parallel with the contour of the road.

3. In a road or the like, an under layer of coarse stones and an upper layer of smaller stones, the spaces between the stones of both layers and between the layers being filled with a soft bituminous binder of identical quality, the larger stones in the lower layer being at the top, face up, close together and in line with the contour of the road.

4. In a road or the like, an under layer, or carrying layer consisting exclusively of relatively large stones with the largest stones at the top and a soft bituminous binder filling the interstices between said stones, and an upper or surface layer of smaller stones and a bituminous binder, in which the proportion of bituminous binder is greatest at the bottom and least at the top.

5. The herein described improvement in the construction of roads and the like, which consists in forming an under layer of relatively large stones, rolling said layer to bring about a classification or grading of stones with the larger stones on top, then pouring a bituminous binder into the voids of the said under layer and over the top thereof, adding smaller stones to the bituminous binder on top to form an upper or surface layer, and rolling this upper or surface layer.

6. The herein described improvement in the construction of roads and the like, which

consists in forming an under layer of relatively large stones, rolling said layer to bring about a classification or grading of stones with the larger stones on top, then 5 pouring a bituminous binder into the voids of said under layer and over the top thereof, adding smaller stones to the bituminous binder on top to form an upper or surface layer, and rolling this upper or surface layer, and rolling this upper or surface layer 10 with a grooved roller to work the larger stones of said layer into the bituminous binder and the smaller ones toward the bottom.

7. The herein described improvement in 15 the construction of roads and the like, which consists in forming a layer exclusively of stones, rolling said layer together to compact it and to securely pack the stones together and then pouring a bituminous binder 20 into the voids of the packed layer.

8. The herein described improvement in 25 the construction of roads and the like, which consists in forming an under layer exclusively of relatively large stones, rolling said layer to compact it, then pouring a bituminous binder into the voids of said under

layer and over the top thereof and adding smaller stones on top to form an upper or surface layer.

9. In a road or the like, a layer consisting 30 of stones packed and bonded by roller pressure exerted on the stones alone and having the voids intervening between them filled with a bituminous binder.

10. In a road or the like, an under layer 35 consisting of relatively large stones, packed and bonded by roller pressure exerted on the stones alone and having the voids intervening between them filled with a bituminous binder, and an upper layer consisting 40 of smaller stones, the bituminous binder extending from the lower layer into the upper layer.

I testimony whereof, we have signed this 45 specification in the presence of two subscribing witnesses.
